(57) **CLAIM**

The ornamental design for an display screen portion with animated graphical user interface for a healthcare command center computing system, as shown and described.

DESCRIPTION

FIG. 1 is a front view of a first image in a sequence of a design for a display screen portion with animated graphical user interface for a healthcare command center computing system, showing the new design; FIG. 2 is a second image thereof; and, FIG. 3 is a third image thereof.

The diagonal hatching in FIGS. 2 and 3 shows a contrast in appearance. The appearance of the image transitions sequentially between FIGS. 1 and 2, and between FIGS. 1 and 3. The process or period in which one image transitions to another image forms no part of the claimed design.

The broken lines showing the display screen portion and the graphical user interface are included for the purpose of illustrating portions of the article and form no part of the claimed design.
